UNITED STATES PATENT OFFICE.

HERBERT PILGER, OF PLAINVIEW, NEBRASKA.

FLY-CHASING SCREEN-DOOR ATTACHMENT.

Application filed March 11, 1922. Serial No. 542,910.

To all whom it may concern:

Be it known that I, HERBERT PILGER, a citizen of the United States, residing at Plainview, in the county of Pierce and State of Nebraska, have invented new and useful Improvements in Fly-Chasing Screen-Door Attachments, of which the following is a specification.

The object of my said invention is the provision of a simple and efficient fly chasing attachment for screen doors, operable manually and independently of the opening and closing of the door from the inner and outer sides thereof.

15 To the attainment of the foregoing, the invention consists in the improvement as hereinafter described and definitely claimed.

In the accompanying drawings, forming part of this specification:—

20 Figure 1 is an elevation of the outer side of a screen door equipped with my improvement.

25 Figures 2 and 3 are sections taken in the planes indicated by the lines 2—2 and 3—3, respectively, of Figure 1.

Figure 4 is a detail front elevation of the wheel comprised in the improvement.

Similar numerals of reference designate corresponding parts in all of the views of 30 the drawings.

The screen door 1, in general, is preferably of the ordinary well known construction though it may be of any other construction compatible with the purpose of my invention 35 without involving departure from the scope of the same as claimed.

In accordance with my invention the screen door 1 is equipped with an upper fixed cross-bar 2, and at a point immediately above

40 its intermediate cross-bar 3 and preferably adjacent to its swinging edge 4 the door is provided with an opening 5, Figure 2, formed through the wire screen 6.

45 Mounted in a bracket 7, fixed to the door frame, and arranged in front of and slightly above said opening 5 is a pulley 8. An upper pulley 9 is mounted in a bracket 10 on the attachment bar 2, and is arranged at right angles to the pulley 8.

50 At 11 is a spindle carried by the attachment bar 2, and at 12 is a fly chasing wheel mounted on the said spindle 11, in parallelism or substantial parallelism with the face or outer side of the door, and having 55 blades 13 which are preferably, though not

necessarily, pitched in the direction of their widths, Figures 2 and 3, with a view to circulating air after the manner of a fan when the wheel is rotated. The wheel 12 is spaced in front of the bar 2, and is provided with 60 a hub 14, Figures 2 and 3.

Connected to and extending upwardly from the frame bar 3 of the door 1 is a retractile spring 15, and connected to the upper end of the spring 15 is a cable 16 wound about and connected to the hub 14. A cable 16^x is also connected to and wound several times about the wheel hub 14, and is passed to and over the pulley 9 and downwardly and about the pulley 8 and through the opening 70 5 in the screen 6, Figures 1 and 2. At its lower end and at the inner side of the door 1 the said cable 16^x is provided with a handle 17 and a stop 18, the latter to limit the movement of the end portion of the cable 75 forwardly through the opening 5.

On the stretch of the cable 16^x between the pulleys 8 and 9 is a handle 19, said handle being preferably connected to said cable stretch by a piece of cable 20 interposed between the handle and the cable 16^x 80 as shown at the left of Figure 1.

In the practical use of my improvement when the handle 17 is pulled inwardly, relative to the door 1, or the handle 19 is pulled 85 downwardly, the wheel 12 will be rotated to frighten flies and cause the same to leave the door, and at the same time the spring 15 will be expanded or put under tension. On the release of the pulled handle, the 90 spring 15 in resuming its normal state will rotate the wheel 12 in the opposite direction so that the slack of the cable 16^x will be taken up on the hub 14.

95 It will be gathered from the foregoing that precedent to opening the door 1 a person at the outer side of the door has but to pull downwardly on the handle 19 to actuate the wheel 12 and frighten flies from the door. The handle 19 may then be used, if 100 desired, as a pull for the convenient opening of the door. It will also be gathered that the rotation of the wheel 12 will operate to so frighten the flies that there will be but little liability of flies passing through the 105 door way while the door is open.

Precedent to opening the door a person seeking to pass outwardly has but to pull the handle 17 and rotate the wheel 12 in 110 order to frighten flies from the door and

lessen the liability of flies entering the door way while the door is open.

I have entered into a detailed description of the construction and relative arrangement 5 of the parts embraced in the present and preferred embodiment of my invention in order to impart a full, clear and exact understanding of the said embodiment. I do not desire, however, to be understood as confining myself to the said specific construction and relative arrangement of parts inasmuch as in the future practice of the invention various changes and modifications may 10 be made such as fall within the scope of my 15 invention as defined in my appended claims.

Having described my invention, what I claim and desire to secure by Letters-Patent, is:—

1. The combination with a screen door, a 20 fly frightening wheel mounted at the outer side thereof, a cable having one end engaging around the hub of the wheel and secured thereto, a retractile spring connected with

the door and the opposite end of the cable, a further cable also having one end engag- 25 ing around the hub of the wheel and secured thereto, and handles connected with the last mentioned cable, one of the handles being arranged at the outer side of the door and the other handle being arranged at the inner side of the door, the opposite end of the last mentioned cable extending through an opening within the screen door.

2. The combination of a screen door, a fly frightening wheel mounted at the outer 35 side thereof, a cable having one end engag- 40 ing around the hub of the wheel and secured thereto, a retractile spring connected with the door and the opposite end of the cable, and a handle at the outer side of the door and connected through another cable with the door and wheel and adapted to serve the additional service of a door pull.

In testimony whereof, I affix my signature.

HERBERT PILGER.
